UNITED STATES PATENT OFFICE.

CORNELIUS J. NOLAN, OF TOLEDO, OHIO, ASSIGNOR TO THE LIBBEY GLASS COMPANY, OF TOLEDO, OHIO, A CORPORATION OF OHIO.

ANNEALING-FURNACE.

1,125,154.

Specification of Letters Patent.

Patented Jan. 19, 1915.

Application filed January 15, 1913. Serial No. 742,136.

To all whom it may concern:

Be it known that I, CORNELIUS J. NOLAN, a citizen of the United States, and a resident of Toledo, in the county of Lucas and State of Ohio, have invented a certain new and useful Annealing-Furnace; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates particularly to annealing ovens for use in connection with the manufacture of glass articles, but is not limited to such use as it may be employed in any connection for which it may be adapted or appropriate.

In the use of the present forms of annealing furnaces difficulty is experienced in obtaining a uniform heating and cooling of the articles being annealed, and to partially overcome the objections incident to such uneven annealing, it has been common to subject the articles to a second and sometimes a third annealing operation, thus necessitating at least a double handling of the articles and very materially increasing the operating expense of the plant both as to fuel and labor.

The object of my invention is the provision of an annealing furnace or oven of the character described, which is adapted to effect a uniform heating and cooling of all articles disposed therein, whereby to overcome the defects incident to the use of the annealing ovens heretofore employed, and to obviate the necessity of subjecting articles to a plurality of annealing operations to obtain commercially practical and satisfactory results, thus saving a considerable part of the present cost of annealing cut glass ware or the like.

A further object of the invention is the provision of an annealing furnace, which is so constructed, both with relation to the relative arrangement of the fire-flues and oven chamber and the manner of carrying articles therein for annealing, as to render a very material saving in fuel in the operating of the furnace and to uniformly heat and cool the articles in the oven.

55 The invention is fully described in the

following specification, and while, in its broader aspect, it is capable of embodiment in numerous forms, a preferred embodiment thereof is illustrated in the accompanying drawings, in which—

Figure 1 is a central vertical section of a furnace embodying my invention. Fig. 2 is a side elevation thereof, and Figs. 3 and 4 are enlarged cross-sections thereof taken on the lines *x*, *x* and *y*, *y*, respectively, in Fig. 1.

Referring to the drawings 1 designates the outer casing or wall of the furnace, which is of upright cylindrical form with its upper end portion contracted and terminating at its top in an outlet flue 2 for the products of combustion. Within the lower portion of the chamber which is formed by the casing 1 is a fire-chamber 3 in which, should gas be employed as a fuel, are disposed a plurality of gas-burners 4 that are carried, in the present instance, by a common circular feed-pipe 5 having connection with a suitable supply-pipe 6 extending from any suitable source of gas supply.

The roof of the fire chamber is designated 7 and is supported by a plurality of posts or standards 7^a, or in any other suitable manner. Rising from the roof 7 of the fire-chamber within the casing 1, in preferably concentric spaced relation thereto, is an interior wall 8, which forms an interior annealing oven 9 that is round in cross-section, and co-operates with the outer wall 1 to form an annular flue 10 therebetween, which flue communicates at its lower end with the fire-chamber 3 around the edge of the roof 7 and at its upper end with the outlet flue 2.

It will, of course, be understood that the walls 1 and 8 and other parts of the furnace exposed to the direct action of the furnace heat are constructed of fire brick or other material suitable for the purpose.

Mounted for rotary movements within the annealing oven 9 is an article carrying rack which comprises, in the present instance, a vertical shaft 11 from which a plurality of equidistantly spaced flanges or partitions 12 radiate, as shown. The shaft 11 is journaled at its lower end in a center pedestal-bearing 13 in the top of the fire-chamber roof 7, which also forms the floor of the annealing oven, and has its upper end journaled in a center bearing 14 in the top portion of the oven wall. The flanges or partitions 12 of the rack extend at their outer edges in close

proximity to the oven wall and coöperate to divide the oven into a plurality of vertically elongated annealing compartments of sectoral form in cross-section. Each of the rack 5 compartments has its opposite side walls, or those formed by the flanges 12, provided with a plurality of vertically spaced transversely disposed grooves or guideways 15, into oppositely-disposed registering ones of 10 which the respective edges of article carrying shelves 16 may be inserted in properly spaced superimposed order.

Provided in one side of both walls 1 and 8 of the furnace and extending across the 15 flue 10 is a filling opening 17, which is formed by a casing 17^a and opens communication between the interior of the oven 9 and the exterior of the furnace, and is preferably closed by inner and outer doors 18 and 20 19, respectively. The outer door is retained closed by latch and hook members 20, or in any other suitable manner. The opening 17 substantially corresponds in shape and size 25 to the outer open side of each annealing compartment of the rack to enable the shelves 16 with articles thereon to be introduced through the door opening and inserted in proper position within the registering compartment or removed therefrom as desired. 30 When a rack compartment is in register with the filling opening the outer edges of its side walls or flanges 14 are in close proximity to the inner side edges of the casing 17^a to prevent cool air from entering any other compartment than that which is in filling position.

Attached, in the present instance, to the lower end portion of the shaft 11 below the rack flanges 12 is a crown-gear 21 with 40 which a bevel gear 22 on a subjacent horizontal shaft 23 meshes. This shaft projects through a bearing at its inner end in a standard 24. Rotation may be communicated to this shaft in any suitable manner for slowly 45 rotating the rack.

In the use of my improved annealing furnace the rack compartments are successively turned into register with the opening 17 and filled with articles to be annealed by the introduction of filled shelves 16 through said 50 opening and their insertion into desired receiving grooves in the walls of the compartment, or if desired the articles may be placed upon shelves in position within the 55 compartment. When all of the compartments have been filled in this manner the filling opening is closed by the doors 18 and 19, or in any other suitable manner, and the 60 driving means for the rack started to cause the rack to slowly rotate within the oven. The oven is quite highly heated during the introduction of the articles therein, and after the filling opening has been closed the 65 heat within the oven is slowly raised to the desired temperature and then gradually low-

ered to permit a slow heating and cooling of the articles to effect an annealing thereof, as is well understood in the art.

It is evident by the use of an oven of this character having a rotating article carrying rack that the articles are uniformly heated and cooled, as the turning of the same within the oven prevents any of the articles from standing in a position within the oven which might not be as highly heated as some other points in the oven. The rotating of the rack within the oven and the registering of a single compartment with the filling opening during the filling of the respective compartments also enables each compartment to be 75 filled without cooling the other compartments, while the compartment being filled is also heated to a suitable temperature to prevent a chilling of the articles when placed therein and prior to the turning of 80 the compartment from register with the filling opening.

I wish it understood that my invention is not limited to any specific construction, form or arrangement of the parts except in 90 so far as such limitations are specified in the claims.

Having thus described my invention, what I claim as new and desire to secure by Letters Patent, is,—

1. In an annealing furnace having inner and outer concentric cylindrical walls forming an annealing oven and an encircling jacket, said walls having filling openings therethrough into the oven, a rotatable rack 100 mounted rotatably within the oven having a plurality of vertically disposed closed partitions extending to the wall of the furnace and a plurality of horizontal closed partitions forming with the inner wall a 105 plurality of article-receiving closed compartments.

2. In an annealing furnace having inner and outer walls forming an annealing oven and an encircling jacket, said walls having filling openings therethrough into the oven, an article-carrying rack rotatably mounted in said oven and being substantially co-extensive therewith in cross-section, said rack having a plurality of vertically disposed 110 closed partitions extending radially to the inner wall of the furnace and horizontal closed partition in each section forming with the inner wall a plurality of closed article receiving compartments around the 115 axis of the rack and a plurality of vertically disposed sections adapted to register with the filling opening.

3. In an annealing furnace having inner and outer concentric cylindrical walls forming an annealing oven and an encircling jacket, a rotatable rack having a plurality of vertically disposed closed partitions extending radially to the inner wall of the furnace and horizontal closed partitions form- 120 125 130

ing a plurality of article-receiving closed compartments vertically disposed in a plurality of sections and a heater located beneath the annealing chamber and communicating peripherally with the jacket.

5 In testimony whereof, I have hereunto

signed my name to this specification in the presence of two subscribing witnesses.

CORNELIUS J. NOLAN.
